UNITED STATES PATENT OFFICE.

WILLIAM H. HOLLAR AND HARRY F. BALOU, OF PHILADELPHIA, PENNSYLVANIA;
SAID BALOU ASSIGNOR TO SAID HOLLAR.

ELECTRICALLY-CONTROLLED LOCK.

1,051,588.

Specification of Letters Patent. Patented Jan. 28, 1913.

Application filed June 3, 1909. Serial No. 499,903.

To all whom it may concern:

Be it known that we, WILLIAM H. HOLLAR and HARRY F. BALOU, of Philadelphia, in the State of Pennsylvania, have invented a 5 certain new and useful Improvement in Electrically- Controlled Locks, whereof the following is a specification, reference being had to the accompanying drawings.

Our invention is applicable to a safe or 10 vault having a door and door frame provided with bolt work and a slide bar operatively connecting said bolt work with a spring or other motor arranged to unlock said bolt work by means of said slide bar, 15 normally under control of a time lock.

It is the object of our invention to provide electrically controlled means distinct from said time lock and capable of preventing unlocking movement of said slide bar 20 when the latter is released by the time lock or other device by which its motion is normally determined.

The form of our invention hereinafter described, comprises a detent pawl pivoted 25 upon the door in such relation to said slide bar as to directly engage a recess in the latter; a tripping lever fulcrumed intermediate of its length, and arranged to normally hold the free end of said pawl in engagement 30 with the recess in said slide bar and normally prevent its unlocking movement; a plunger operatively connected with the opposite end of said tripping lever; a magnet core carried by said plunger; a solenoid in 35 operative relation with said core; a circuit including said solenoid and a source of current exterior to said vault; a switch in said circuit; a time lock on said door arranged to close said switch; and, another switch in 40 said circuit; whereby the bolt work may be released for unlocking movement only when both of said switches respectively controlled by the time lock and by other means, are closed. As hereinafter described, the means 45 other than the time lock adapted to control a switch in the electric circuit, may include a combination lock, so that said switch may only be operated by one who knows the combination, or other means may be employed 50 for operating said auxiliary switch.

Our invention comprises the various novel features of construction and arrangement hereinafter more definitely specified.

In said drawings; Figure I is an inner 55 face view of a fragment of a vault door con-

veniently embodying our improvement. Fig. II is a sectional view of said door, taken on the line II, II in Fig. I. Fig. III is a fragmentary elevation showing the engaged position of the unlocking bar and detent 60 mechanism indicated in dotted lines in Fig. I. Fig. IV is a fragmentary elevation similar to Fig. III, but showing the disengaged position of said bar and detent mechanism. Figs. V to XIII inclusive are diagrams 65 showing respective modifications of our invention.

Figs. I and II, show a fragment of a circular door 1, conveniently provided with bolt work of the type shown in Letters Patent of the United States #621,341 dated March 21, 1899, and comprising a circular series of radially reciprocatory lock bolts 2, having racks 3, at their inner ends respectively in mesh with pinions 4. All of said 70 pinions 4 are in mesh with the spur wheel 6, which is mounted to turn on the stud 7, carried by the door, so as to simultaneously thrust all of said bolts 2 outwardly to lock the door, or draw them inwardly to unlock 80 the door; said bolts being arranged to engage suitable sockets 8 in the door frame 9, indicated in Fig. V. The unlocking movement of said bolts 2 is conveniently effected by the spring motor 10, which is supported 85 by the frame plate 11, rigidly connected with said door 1, by standards 12, extending through slots 13, in said spur wheel 6. Said spring motor 10, is of well known construction, having pairs of plungers 15 and 90 16, at its opposite ends, respectively connected with the reciprocatory cross-heads 17 and 18, which are respectively connected in rigid relation with the slide bars 20 and 21, having racks at their outer ends respectively in mesh with pinions 4. The dotted lines 22 shown in Fig. I, indicate openings in the spur gear 6, which permit the latter to turn with respect to the cross-heads 17 and 18. It is to be understood that said 95 slide bars 20 and 21, are balanced in horizontal position, so that their weight does not at any time effect their movement. Said slide bar 20, has the recess 23 for the detent pawl 24, which is fulcrumed on the stud 25, 100 projecting from the door 1. As shown in Fig. III, the free end of said pawl 24, is normally held in said recess 23, by the dead-locking lever 27, which is fulcrumed intermediate of its length, upon the stud 28, 110

projecting from said door 1. The opposite end of said deadlocking lever 27, is connected by the pivot 29, with the plunger 30, carrying the magnet core 31, within the 5 solenoid 32, against the spring 33. When said solenoid is energized as hereinafter described, said core 31, and deadlocking lever 27, are shifted to the position shown in Fig. IV, thus permitting the pawl 24, to be raised 10 to the position shown in said figure, by the unlocking movement of said slide bar 20, in the direction of the arrow shown thereon. The stud 34, which projects from said door 1, limits the movement of said 15 pawl 24, and deadlocking lever 27. As indicated in Fig. I, said door is provided with an ordinary time lock 36, and with two electrically controlled combination locks 37 and 20 38, constructed and arranged as shown and described in Letters Patent of the United States #686,073 dated November 5, 1901, and comprising circuit connections extending through the conduits 40, to exterior 25 switch mechanism, whereby said locks may be operated. Said time lock and electrically controlled combination locks on the door, may be employed to complete a circuit extending through said conduits 40, and including the solenoid 32, and an external 30 source of current 41, so as to release the slide bar 21 as hereinafter described. Fig. V shows the most complex arrangement for energizing said solenoid 32, including a circuit which connects said solenoid with the 35 generator 41, and includes five switches, viz:—the switch 42, local to the generator; the switch 43, arranged to be closed by manually setting the combination lock 44, which is on the door frame 9; the switch 40 45, arranged to be closed by manually setting the combination lock 46, on the door 1; the switch 48, arranged to be closed by the operation of the electrically controlled combination lock 38; and, the switch 50, arranged to be closed by the operation of the 45 time lock 36.

Fig. VI shows circuit connections similar to Fig. V, but omitting the switch 45. Fig. VII shows circuit connections similar to 50 Fig. V, but omitting the switch 48. Fig. VIII shows circuit connections similar to Fig. V, but omitting the switch 43. Fig. IX shows circuit connections similar to Fig. V, but omitting the switches 45 and 48. Fig. 55 X shows circuit connections similar to Fig. V, but omitting the switches 43 and 45. Fig. XI shows a circuit similar to Fig. X, but having a shunt parallel with the switch 48, and including the switch 51, arranged 60 to be closed by the operation of the electrically controlled combination lock 37. It may be observed that by this arrangement, when the switches 42 and 50, are closed, the circuit to energize the solenoid 32, may be 65 closed by operation of either of the locks

37 or 38. Fig. XII shows circuit connections similar to Fig. X, but including a shunt circuit parallel with the switch 48, for the operation of said electrically controlled combination lock 38. Fig. XIII 70 shows the simplest arrangement for energizing said solenoid 32, including a circuit which connects said solenoid with the generator 41, solely under control of the switch 42.

It may be observed that in all of the forms of our invention above described, the detent pawl is so arranged as to positively prevent the opening movement of the lock when the latter is released by the time lock 80 or other device by which its motion is normally determined.

It is to be understood that the coils of said solenoid may be so connected and energized that the plunger 30, may be thereby 85 shifted both in the direction described to release the detent pawl 24, and in the opposite direction to engage said detent pawl.

We do not desire to limit ourselves to the precise details of construction and arrangement above described, as it is obvious that various modifications may be made therein without departing from the essential features of our invention as defined in the appended claims.

We claim:—

1. In a vault, the combination with a door and door frame provided with bolt work; of a slide bar operatively connected with said bolt work; a spring motor arranged to unlock said bolt work by means of said slide bar; a detent pawl having an inclined end arranged to engage an inclined recess in said bar and prevent its unlocking movement; a deadlocking lever fulcrumed 100 intermediate of its length and arranged to normally hold the free end of said pawl in said recess in said slide bar and normally prevent its unlocking movement; a plunger operatively connected with the opposite end 105 of said deadlocking lever; a magnet core carried by said plunger; a solenoid in operative relation with said core; a circuit including said solenoid and a source of current exterior to said vault; and, a switch 110 in said circuit; whereby said bolt work is detained in locked position until said switch is closed, and said pawl is automatically thrown out of said recess by movement of said bar.

2. In a vault, the combination with a door and door frame provided with bolt work; of a slide bar operatively connected with said bolt work; a spring motor arranged to unlock said bolt work by means of said slide 125 bar; a detent pawl having an inclined end arranged to engage an inclined recess in said bar and prevent its unlocking movement; a deadlocking lever fulcrumed intermediate of its length and arranged to nor- 130

5 mally hold the free end of said pawl in said recess in said slide bar and normally prevent its unlocking movement; a plunger operatively connected with the opposite end of said
 10 5 dead-locking lever; a magnet core carried by said plunger; a solenoid in operative relation with said core; a circuit including said solenoid and a source of current exterior to said vault; a switch in said circuit; a time lock on said door, arranged to close said switch; and another switch in said circuit, independent of said time lock; whereby, said bolt work is detained in locked position until said tripping lever is tripped, and,
 15 15 said pawl is then automatically thrown out of said recess by movement of said bar.

3. In a vault, the combination with a door and door frame provided with bolt work; of a slide bar operatively connected with said bolt work; a spring motor arranged to unlock said bolt work by means of said slide bar; a detent pawl arranged to engage a recess in said bar and prevent its unlocking movement; a deadlocking lever fulcrumed 25 intermediate of its length and arranged to normally hold the free end of said pawl in said recess in said slide bar and normally prevent its unlocking movement; a plunger operatively connected with the opposite 30 end of said deadlocking lever; a magnet core carried by said plunger; a solenoid in operative relation with said core; a circuit including said solenoid and a source of current exterior to said vault; a switch in said circuit; a time lock on said door, arranged to close said switch; a second switch in said circuit, independent of said time lock; and a combination lock arranged to operate said second switch; whereby said bolt work is 35 detained in locked position until said switches are closed.

4. In a vault, the combination with a door and door frame provided with bolt work; of a slide bar operatively connected with said bolt work; a spring motor arranged to unlock said bolt work by means of said slide bar; a detent pawl arranged to engage a recess in said bar and prevent its unlocking movement; a deadlocking lever fulcrumed 45 intermediate of its length and arranged to

normally hold the free end of said pawl in said recess in said slide bar and normally prevent its unlocking movement; a plunger operatively connected with the opposite end of said deadlocking lever; a magnet core 55 carried by said plunger; a solenoid in operative relation with said core; a circuit including said solenoid and a source of current exterior to said vault; a switch in said circuit; a time lock on said door, arranged to close said switch; a second switch in said circuit, independent of said time lock; and an electrically controlled combination lock arranged to operate said second switch; whereby said bolt work is detained in locked 60 position until said switches are closed.

5. In a vault, the combination with a lock slide bar having an obtuse angular recess in a longitudinal edge thereof; of a detent having an obtuse angular end fitted to the 70 recess in said bar; a pivotal support for said detent; a stud limiting the movement of said detent; a deadlocking lever having one end arranged to removably engage the free end of said pivoted detent; a fulcrum 75 intermediate of the length of said deadlocking lever; a solenoid core pivotally connected with the opposite end of said deadlocking lever; a spring tending to shift said deadlocking lever into contact with said 80 stud; a solenoid in operative relation with said core; and, an electric circuit including said solenoid, a source of current and a switch; whereby, unlocking movement of said bar is prevented by the engagement of 85 said deadlocking lever with said detent, and, locking movement of said bar is permitted when said deadlocking lever is released; movement of said detent to release said locking bar being effected solely by 90 movement of the latter.

In testimony whereof, we have hereunto signed our names at Philadelphia, Pennsylvania, this 13th day of May 1909.

WILLIAM H. HOLLAR.
HARRY F. BALOU.
